UNITED STATES PATENT OFFICE.

HENRY E. RUSSELL, JR., OF NEW BRITAIN, CONNECTICUT, ASSIGNOR TO
THE RUSSELL & ERWIN MANUFACTURING COMPANY, OF SAME PLACE.

DESIGN FOR A DOOR-KNOB.

SPECIFICATION forming part of Design No. 15,754, dated January 27, 1885.

Application filed December 22, 1884. Term of patent 14 years.

To all whom it may concern:

Be it known that I, HENRY E. RUSSELL, Jr., of New Britain, in the county of Hartford and State of Connecticut, have originated and produced a new Design for a Door-Knob, of which the following is a full, clear, and exact description, reference being had to the accompanying sheet of drawings, forming part of this specification.

10 Figure 1 is a side elevation of my newly-designed door-knob, and Fig. 2 is a front elevation of the same.

The contour of my door-knob, as viewed in side elevation, even when its corrugated or scalloped outline is not taken into consideration, is materially different from that of any prior door-knob known to me in the following respects: The front face, A, is on the arc of a circle, and occupies but about one-third 20 of the length of the knob. From the front

face, A, to the shank B is the rear surface, C, of the convex contour shown and occupying about two-thirds of the length of the knob, exclusive of the shank B. I ornament these faces by a series of concentric depressions, a, 25 which present a corrugated or scalloped outline, as shown. The depressions may extend substantially over the whole surface of the knob, if desired; but I prefer to leave a smooth portion between the faces A and C that is 30 wider than the space occupied by two adjoining depressions, all as shown in Fig. 1.

I claim as my invention—

The design for a door-knob, substantially as herein shown and described.

HENRY E. RUSSELL, JR.
